UNITED STATES PATENT OFFICE.

GEORGE E. SCHACHT, OF PLAINFIELD, NEW JERSEY.

FARE-REGISTERING DEVICE.

Application filed January 7, 1924. Serial No. 684,816.

This invention has relation to registering devices and has particular reference to a device which is especially designed for indicating and registering the fares paid on rides in amusement parks, although the same is not necessarily restricted to this use.

One of the principal objects of the present invention is to provide an apparatus by means of which the total number of fares paid is registered and further by means of which apparatus the individual amounts or numbers are temporarily displayed.

More specifically the invention contemplates the combination with a bank of electric lamps, and a registering device including a recording mechanism for the total and means for actuating the same, of a circuit closing means operated by the actuating means for simultaneously closing the circuit to certain of said lamps whereby the number of fares registered will be displayed on the bank of lamps conforming to the individual number of fares registered on the registering mechanism.

The invention contemplates as a still further object a fare registering device which is comparatively simple in its construction and mode of operation, which is highly efficient in its purpose and which may be produced and sold at a minimum cost.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawings—

Figure 1 is a sectional plan view of the registering device taken approximately on the line indicated at 1—1 of Fig. 2.

Fig. 2 is a vertical longitudinal sectional view therethrough taken approximately on the line 2—2 of Fig. 1.

Fig. 3 is a fragmentary sectional plan view taken approximately on the line 3—3 of Fig. 2.

Fig. 4 is a fragmentary sectional view taken approximately on the line 4—4 of Fig. 3.

Fig. 5 is a similar view taken approximately on the line 5—5 of Fig. 3.

Fig. 6 is a fragmentary sectional view taken approximately on the line 6—6 of Fig. 1.

Fig. 7 is a plan view of the device with the cover plate opened.

Fig. 8 is a diagrammatic view illustrating the wiring of the apparatus.

Referring to the drawings by characters of reference, the registering device includes

a casing or housing 10 within which a registering mechanism designated generally by the character 11 is mounted.

The registering mechanism includes a main shaft 12 and a countershaft 13.

A plurality of elements 14, 15, 16, 17, 18 and 19, each having a peripheral dial 20 on which suitable numerical indicia are inscribed, are loosely mounted on the main shaft 12 for rotation.

The element 14 inscribed with the unit indicia on its dial is provided with a ratchet 21 with

which a pawl 22 engages, said pawl being carried by a pinion 23 loosely mounted on the main shaft 12 adjacent one end thereof.

The element 14 is further provided with a gear 24 which meshes with a gear 25 loosely mounted on the countershaft 13.

The gear 25 has secured thereto a gear 26 having a single tooth.

Between the elements 14 and 15 a pinion 27 is loosely mounted on the

main shaft and said pinion 27 has pivoted thereon a pawl 28 which engages with the

ratchet 29 on the element 15, the element 15 being further provided with a gear 30 meshing with a gear 31 loosely mounted on the

counter shaft and which gear 31 has secured thereto a gear 32 having a single tooth.

The elements 14 and 15 are restricted to turning movement in one direction by means of

spring pressed pawls 33 which engage with

ratchets 34. Upon turning of the pinions 23 and 27 in one direction the elements 14 and

15 will be turned therewith while said elements will be restrained against retrograde

movement when the said pinions turn in the

opposite direction, thus forcing the pawls 22

and 28 to ratchet over their ratchets 21 and

29. The gears 24 and 30 and the gears 25

and 31 which mesh therewith are each pro-

vided with ten teeth whereby one complete

rotation of the pinion 23 will effect the move-

ment of the pinion 27 one-tenth of a revolu-

tion and correspondingly through it pawl

and ratchet connection the movement of the

dial of the element 15 one-tenth of a revolu-

tion. The gear 32 having a single tooth is

adapted to mesh with a gear 35 having ten

teeth and the element 16 is provided with a second gear 36 having ten teeth which meshes with a ten toothed gear 37 on the counter shaft 13 to which a gear 38 having a single tooth is secured for rotation therewith. The remaining elements 17, 18 and 19 are of substantially the same construction together with the connecting gears on the counter shaft to complete a recording mechanism 11 having any desired number of digits which are displayed through openings 39 in the rabbeted portion 40 of the casing over which rabbeted portion a cover plate 41 is mounted, the same having hinged connection as at 42 and provided at its free edge with a suitable lock 43 engageable with a keeper 44.

Within the casing a transverse shaft 45 is supported parallel to and spaced from the registering mechanism and upon this shaft 20 there is journaled for rocking movement a plurality of groups of arms in the first group of which the arms 46, 47, 48, 49, 50, 51, 52, 53, 54 and 55 are arranged and in the second group of which the arms 56, 57 and 58 are arranged. Each of said arms is provided at one end with an arcuate head 59 having rack teeth which, upon swinging of the arms respectively, engage with the pinions 23 and 25 27. The arcuate head of the arm 46 is provided with no rack teeth, while the arcuate heads of the arms 47, 48, 49, 50, 51, 52, 53, 54 and 55 are respectively provided with one, two, three, four, five, six, seven, eight and nine teeth. The arcuate heads of the arms 30 56, 57 and 58 are respectively provided with one, two and three teeth. Each of the arms is connected at the end opposite from the headed end by a coiled contractile spring 60 to the insulating base 61 whereby the springs 35 serve as means for normally swinging the headed ends of the arms upwardly to effect rotation of the pinions with which they engage. In order to lock the arms against movement under the influence of the springs 40 each arm is formed at its free end with a nose 62 which is engaged by a latch 63 pivoted on a transverse shaft 64 mounted parallel to the shaft 45. The several latches are retained on the shaft against lateral movement 45 between stationary abutments 65 and spacing sleeves 66. The tail of each latch is slotted as at 67 and is positioned in the slotted end of a vertical key shaft 68 with a pin 69 passing through the slot 67. The 50 lower ends of the key shaft 68 are provided with heads 70 and the springs 71 are interposed between the heads 70 and the stepped portions 72 of the casing bottom. The key shafts 68 project upwardly through a sleeve bearing 73 and are disposed exteriorly or above the upper wall of the casing 10, said upper ends being provided with indicia bearing keys 74. Each key shaft is provided with a stop element 75 which engages the 55 lower end of the sleeve bearing 73 to limit

the upward movement of the key shaft under the action of the spring 71. Under this arrangement it will be obvious that the arms may be selectively released by downward pressure on the keys 74 which will throw the 70 corresponding latch 63 out of engagement with the nose 62, thus permitting the spring 60 to swing the headed end 59 upwardly to rotate the pinions 23 or 27 for operating the recording mechanism 11.

The temporary registering or indicating mechanism consists of two banks of lamps 80 and 81, one terminal of each lamp of which is connected in series with a common lead wire 82 to one pole or source of supply 83. The opposite terminals of the lamps of the bank 80 are connected by circuit wires 84 with the stationary contacts 85 of a circuit closing device designated generally at 86. The stationary contacts 85 are preferably 85 arranged in a group concentric of a circular base plate 87 of insulating material. Movable contact elements 88 each having an arm 89 are pivoted between bearing ears 90 which are supported for radial inward swinging 90 movement over the central group of stationary contacts 85. All of the movable contact elements are connected in series with a circuit wire 91 which leads to one of the contact elements 92 of a circuit breaker 93, the other contact element 94 of which is connected by a circuit wire 95 to the common return wire 96 leading to and connected with the opposite pole of the source of supply 83. The circuit closing device 86 is mounted in the casing or 100 housing 10 and the arms 89 of the movable contacts 88 are connected by cables 97 respectively with the group of arms 46, 47, 48, 49, 50, 51, 52, 53, 54 and 55 whereby the said movable contact elements 88 will be simultaneously thrown into engagement with the stationary contacts 85 upon upward movement of the arm when the same is released by pressure on the key 74. Thus at the same time the tail 98 of the arm selectively 110 released will bridge the contact elements 92 and 94 of the circuit breaker 93 to complete the circuit to the group of lamps which have been selectively closed by the engagement of the movable contact 88 with the stationary contacts 85. This will produce on the bank 80 a numeral corresponding to the number of digits on the recording mechanism and will indicate the unit number on each actuation of the registering or recording device. The group of keys 74 which control the arms 56, 57 and 58 operate a separate bank of lamps 81 which indicate the tens digits. A circuit closing device 100 which is substantially identical with the circuit closing device 86 includes a circular base 101 of insulating material in which a group of stationary contacts 102 are concentrically arranged, said stationary contacts being connected by circuit wires 103 with the various 120 125 130

lamps of the bank 81. A plurality of movable contact elements 104 having arms 105 pivoted between bearing ears 106 are adapted to be swung radially inward over the stationary contact elements 102. The arms 105 are connected by cables 107 to the corresponding arms 56, 57 and 58. The movable contact elements 104 are connected in series by a common return wire 108 with the contact member 109 of a circuit breaker 110, the other contact member 111 of which is connected by a circuit wire 112 with the common return wire 96 to the source of supply 83. The tails 113 of the second group of arms are designed, when the arm is released and swung upwardly under the influence of the spring 60, to bridge the contacts 109 and 111 so that the circuit to certain of the lamps of the bank 81 is completed when the key 74 is pressed downwardly to release one of the arms 56, 57 or 58. In order to provide means for returning the arms to normal position against the action of the spring 60 for re-engaging the noses 62 with the latches 63, a resetting bar 114 preferably of insulating material is mounted within the casing in a position traversing all of the arms. The opposite ends of the resetting bar 114 extend through slotted tubular standards 115 within which coiled expansion springs 116 are arranged for normally moving the bar upwardly to the limit of its movement. A resetting shaft 117 is attached centrally to the resetting bar 114 and extends upwardly through a depending bearing sleeve 118 with its upper end 119 protruding through the upper wall of the casing and into a solenoid housing 120. The upper end 119 constitutes the laminated core which is movable through the solenoid spool 121 arranged in the housing 120. The winding 122 of the solenoid spool is arranged in a circuit 123 which includes a source of supply 124 and spaced contact elements 125. The contact elements 125 are adapted to be arranged in the path of movement of the cars of the amusement device and are designed to be bridged by a shoe 126 carried on the car 127 when the same passes a predetermined point in the ride, which point will have given a spotter or observer ample time to observe the individual numbers registered on the banks of lamps 80 and 81. It thus follows that after the arms have been moved upwardly under the influence of the springs 60, a downward pressure on the reset key 119 will move the reset bar 114 downwardly thereby swinging the arm which has been released downwardly and the tail 98 upwardly until the nose 62 is forced beyond its latch 63 which resets the device for further manipulation. In order to return the movable contact elements 88 and 104 to a normal position out of contact with the stationary contact elements 85 and 102, springs

128 are employed. The radial outward swinging movement is arrested by an annulus 129.

In use and operation, assuming the operator of the device desires to register and record ten fares, the nought key on the right hand group of keys of Fig. 7 is depressed and simultaneously the one key on the left hand group of Fig. 7 is depressed. This depresses the key shifts 68 of said keys and swings the latches 63 upwardly until the noses 62 of the arms 46 and 56 are released. The spring 60 of said arms 46 and 56 will move the tails 98 and 113 downwardly into engagement with the spaced contacts 92 and 93 of one of the circuit closers 94 and the spaced contacts 109 and 111 of the other circuit closer 110. Simultaneously the upward movement of the arcuate headed end 59 of the arm 46, due to the fact that no rack teeth are formed on said head, will therefore not effect rotation of the pinion 23, thus the dial of the element 14 will show through its opening 39 a nought. At the same time the arcuate headed end 59 of the arm 56 having a single tooth will rotate the pinion 27 a tenth of a revolution which, in turn, through the engagement of the pawl 28 with the ratchet 29 will rotate the element 15 a tenth of a revolution to show through the tens opening 39 the character one indicating ten on the recording mechanism. Simultaneously with the upward movement of the arms 46 and 56 a pull will be exerted on the cables 97 and 107 connected therewith which will throw the movable contact element 88 of the circuit closer 86 into engagement with the stationary contacts 85 and one of the movable elements 104 into engagement with the stationary contact elements 102 of the circuit closer 100. The circuits thus being completed to the banks 80 and 81 will energize the selected group of lamps thereby displaying the character ten. After this manipulation of the device has been completed and the car 127 reaches the point in its path of travel where the spaced contacts 125 are arranged, the shoe 126 will bridge the contacts 125 and close the circuit 123, thereby energizing the solenoid to move the core 119 downwardly together with the reset bar 114. When the reset bar moves downwardly it will return the arms to their normal position whereby their noses 62 are again engaged by the latches 63. At the same time slack in the cables 97 and 107 will permit the springs 128 to throw the movable contact elements 88 and 104 radially outward until they contact with the annulus 129, thus deenergizing the groups of lamps of the two banks. The return movement of the head 59 of the arm 56 will effect a retrograde movement of the pinion 27 but the pawl 33 engaging with the ratchet 34 of the element 15 will not permit a retrograde movement of

the element 15 but will permit the pawl 28 to ratchet over the ratchet 29. A similar second operation of the device as heretofore described will operate the recording mechanism to show twenty through the openings 39, while the second registration of ten will be displayed on the banks of lamps 80 and 81.

In using the device for checking the fares of rides in amusement parks, one of the principal difficulties encountered is due to collusion between the collector of re-ride fares and the register of the same who are usually stationed in close proximity to each other at a point where the passengers of the vehicles dismount or elect to remain for a re-ride. To overcome this difficulty it is proposed to separate the register from the collector by stationing the former at a point remote from the collector and at a place where the cars or vehicles pass directly after filling of the same is completed at the starting point and where the operator of the registering device heretofore described will be unable to distinguish the new passengers from the re-ride passengers. The operator of the registering device manipulates the same to show on the lamp banks the number of passengers in the vehicle. This unmistakably displays to a spotter the number which has been registered on the registering mechanism in order that he may check up the number in the car or vehicle. At the same time the registering mechanism totals the entire number for a specified length of time. It is intended that the cover 41 be locked so that the reading of the total is not within view of the operator of the device. It therefore follows that at the end of the day the number of tickets sold is subtracted from the total shown by the registering device and the collector of cash fares for the re-rides must of necessity turn in the difference.

I claim:

1. A fare indicating and registering device, comprising a casing, a registering mechanism, a circuit closing mechanism having a plurality of movable contacts, a plurality of swingingly mounted arms in said casing, and operative connection respectively between said arms and the registering mechanism and said arms and the movable contacts of the circuit closing mechanism, means for normally swinging the arms in a direction to operate the registering mechanism and to close the circuits, means for normally locking said arms against their normal swinging movement, and key operated means for selectively releasing said arms.

2. A fare indicating and registering device including a casing, a counting mechanism for registering the total of fares received and registered, said counting mechanism including an operating pinion, a plu-

rality of pivoted arms within the casing each having racks at one end provided respectively with various numbers of teeth, means connected with said arms for normally moving the same in a direction to cause the teeth to engage and rotate the pinion, means for normally locking said arms against their normal movement, and key operated means for selectively releasing the locking means.

3. A fare indicating and registering device including a casing, a counting mechanism for displaying the total of fares received and registered, said counting mechanism including an operating pinion, a plurality of pivoted arms within the casing each having racks at one end provided respectively with various numbers of teeth, means connected with said arms for normally moving the same in a direction to cause the teeth to engage and rotate the pinion, means for normally locking said arms against their normal movement, key operated means for selectively releasing the locking means, a circuit closer within the casing for controlling a bank of lamps to indicate when energized an amount corresponding to the individual amounts as they are registered on the counting device, and a connection between the movable elements of the circuit closer and the arms.

4. A fare indicating and registering device including a casing, a counting mechanism for displaying the total of fares received and registered, said counting mechanism including an operating pinion, a plurality of pivoted arms within the casing each having racks at one end provided respectively with various numbers of teeth, means connected with said arms for normally moving the same in a direction to cause the teeth to engage and rotate the pinion, means for normally locking said arms against their normal movement, key operated means for selectively releasing the locking means, a circuit closer within the casing for controlling a bank of lamps to indicate when energized an amount corresponding to the individual amounts as they are registered on the counting device, a connection between the movable elements of the circuit closer and the arms, and means for resetting the arms, said means being operable to effect the return of the movable elements of the circuit closer to normal position.

5. A fare registering device including a counting mechanism, a pair of pinions for operating said counting mechanism having respectively a ratchet connection with the units and tens digit dials, a plurality of groups of pivoted arms each having an arcuate head at one extremity formed with various numbers of rack teeth, means for normally swinging the arms in one direction to effect engagement of the rack teeth with the pinions and operation of the counting

mechanism, a latch for normally holding each arm against movement, keys connected with the latches for selectively releasing the same, a depressible reset bar overlying the 5 arms, means for depressing said bar to reset the arms released, and an indicating device for temporarily displaying the individual amounts as they are registered comprising a bank of electric lamps, and a selective 10 circuit closing means therefor operative by the arms of each group for temporarily indicating and displaying the numbers as they are individually registered on the registering mechanism.

15 6. A fare indicating and registering device, including a bank of electric lamps certain combination of which are adapted to be energized to display numerals for temporarily indicating and displaying the individual amounts as registered, an apparatus for controlling the indicating device and for displaying the total of the individual amounts as they are indicated, comprising a housing, a registering mechanism, a common 20 means for operating the registering mechanism and simultaneously energizing a combination of the lamps, means automatically operable after a predetermined display of the individual amounts registered, for resetting said common operating means, and simultaneously effecting the de-energization 25 of the energized lamps.

30 7. A registering device including a counting mechanism for designating total amounts, a key-operated means for actuating the counting mechanism, and means operable by said key-actuated means for temporarily indicating the individual amounts as they are registered on the counting 35 mechanism, said indicating mechanism comprising a bank of lamps, a circuit including a source of supply having a common conductor connected in parallel with the lamps, a plurality of switches having spaced contacts arranged in said circuit and adapted to be bridged by the respective key 40 operated elements to close the circuit, a common circuit closer including a series of stationary contact elements leading to the respective lamps of the bank, and a plurality of movable contact elements of different configurations 45 operatively connected with the key-operated elements for movement into engagement with the stationary contact elements to selectively close the circuit to certain combinations of the lamps of the bank. 50

55 8. A registering device including a counting mechanism for designating total amounts, a key-operated means for actuating the counting mechanism; and means operable by said key actuated means

for temporarily indicating the individual amounts as they are registered on the counting mechanism, said indicating mechanism comprising a bank of lamps, a circuit including a source of supply having a common conductor connected in parallel with the lamps, a plurality of switches having spaced contacts arranged in said circuit and adapted to be bridged by the respective key operated 65 elements to close the circuit, a common circuit closer including a series of stationary contact elements leading to the respective lamps of the bank, a plurality of movable contact elements of different configurations 70 operatively connected with the key-operated elements for movement into engagement with the stationary contact elements to selectively close the circuit to certain combinations of the lamps of the bank, said key-operated means being normally moved to active position, and locking devices for holding the same inactive and releasable by manipulation of the keys, whereby upon manipulation of the keys the opening of the 75 circuits is out of the control of the operator.

80 9. A registering device including a counting mechanism for designating total amounts, a key-operated means for actuating the counting mechanism; and means operable by said key-actuating means for temporarily indicating the individual amounts as they are registered on the counting mechanism, said indicating mechanism comprising a bank of lamps, a circuit including a source of supply having a common conductor connected in parallel with the lamps, a plurality of switches having spaced contacts arranged in said circuit and adapted to be bridged by the respective key operated 85 elements to close the circuit, a common circuit closer including a series of stationary contact elements leading to the respective lamps of the bank, a plurality of movable contact elements of different configurations 90 operatively connected with the key-operated elements for movement into engagement with the stationary contact elements to selectively close the circuit to certain combinations of the lamps of the bank, said key-operated means being normally moved to active position, and locking devices for holding the same inactive and releasable by manipulation of the keys, whereby upon manipulation of the keys the opening of the 95 circuits is out of the control of the operator, and automatic means for resetting the device to open the circuit after a predetermined display of the individual amounts recorded on the counting mechanism.

100 GEORGE E. SCHACHT.
